UNITED STATES PATENT OFFICE.

ABRAM H. PYLE, OF WEBSTER CITY, IOWA.

DESIGN FOR A VALVE-STEM PROTECTOR.

SPECIFICATION forming part of Design No. 27,067, dated May 18, 1897.

Application filed December 30, 1896. Serial No. 617,515. Term of patent 7 years.

To all whom it may concern:

Be it known that I, ABRAM H. PYLE, a citizen of the United States, residing at Webster City, county of Hamilton, and State of Iowa, **5** have invented a new and ornamental Design for a Valve-Stem Protector, of which the following is a specification.

Figure 1 of the accompanying drawings shows a side elevation of the complete valve-**10** stem protector. Fig. 2 shows a transverse sectional view through the line 3 3 of Fig. 1.

The protector comprises a straight metal tube-section F, circular in cross-section and smooth on its internal and external surfaces. **15** To its base or lower end is fixed a concavo-convex disk F², the curve of which is made

to conform with the shape of the inner tube of a bicycle-tire, and it is made of such thickness that it may lie between the inner and the outer tubes of the tire without distending the outer tube. There is a central opening in the disk of the same size as the opening in the tube. **20**

What I claim is—

The design for a valve-stem protector as **25** shown and described.

ABRAM H. PYLE.
